GARMENT

Esther Hordiner, New York, N. Y.

Application November 23, 1938, Serial No. 241,946

2 Claims. (Cl. 2—270)

This invention relates generally to improvements in garments, but more specifically to draw-string operated closure means for the ends or openings of the leg portion, arm portion and other portions of the garment.

The main object of the invention resides in the provision of a closure means especially applicable to the arm and leg terminals of the garment whereby the extended ends of the arm and leg portions may serve as hand and foot coverings.

A further and incidental object of the invention resides in the provision of a closure means for children's garments wherein the ends of the arm portions may be drawn over the hands and closed to serve as a protection against the cold for the child's hands and also as a covering to prevent thumb sucking, and wherein the ends of the leg portions may be drawn over the feet to serve as protection to the child's feet against the cold and to serve also as temporary walking slippers.

Another object of the invention resides in the provision of a closure means for openings in garments whereby said openings may be tightened about portions of the body such as at the knee, above the knee, at the waistline, at the neckline and about regions of the arms.

These objects and other incidental ends and advantages of the invention will hereinafter appear in the progress of the disclosure and as pointed out in the appended claims.

Accompanying this specification is a drawing showing a preferred form of the invention wherein in corresponding reference characters designate corresponding parts throughout the several views and wherein:

Figure 1 is a front view in perspective showing a child's sleeping garment in either one or two pieces wherein arm and leg terminals are adjustably secured to the wrists and the ankles.

Figure 2 is a view similar to Figure 1 wherein the lower portion of the garment is worn like any other garment.

Figure 3 is an enlarged fragmentary view in elevation of an open and encircling portion of a garment showing a draw-string construction co-operating with a hem and a button secured thereto.

Figure 4 is a sectional view of Figure 3 along the plane 4—4 thereof.

Figure 5 is a partial end view in elevation showing the terminal of an arm portion of a garment closed and drawn beyond and enclosing the hand of the wearer.

Figure 6 is a partial end view in elevation

showing the terminal of a leg portion closed and drawn beyond and enclosing the foot portion of the wearer.

In accordance with the invention and in accordance with a preferred form shown, numerals 10 and 11 indicate the upper and lower portions of a garment, either in one or two pieces, having arm terminals 12 and 13 and leg terminals 14 and 15. The arm and leg terminals may either be secured beyond the hand and foot portions, at 10 the wrist and ankle portions, or along the arm and leg portions.

In order that the invention be applied to the garment, it is necessary that the terminals or open ends of the garment be provided with a hem 16 preferably formed by inwardly turning the lower edge of fabric 17 upon itself and employing a stitching 18. Along the outer wall of hem 16 are provided two spaced and parallel buttonholes or openings 19 and 20 through which the ends of a draw-string 21 passing around and within the hem 16 extend. A button member 22 is adapted to be secured to the outer surface of the hem 16 between the buttonholes 19 and 20, the said button 22 having two horizontally aligned and spaced openings 23, 23 extending inwardly of the perimeter thereof. The button 22 is adapted to be secured to the outer wall of hem 16 by any means such as stitching 24, said stitching 24 affording sufficient clearance for manipulating 30 the draw-string ends through the buttonholes 19 and 20 and through the openings 23, 23.

The ends of the draw-string 21 beyond and adjacent the openings 23, 23 are each terminated in a knot as indicated by numerals 25 and 26 in 35 order that the ends of the draw-string 21 may be prevented from being drawn inwardly of openings 23, 23 and in order to be grasped by the fingers for drawing the draw-string.

By pulling at the ends of draw-string 21, the hem 16 is tightened, such tightening being made secure by tying the ends of the said draw-string at the adjusted position. In order to loosen the adjustment, the tied ends are merely undone. When the child is put to bed, the arm portions of the garment may be drawn over the hands and the draw-string tightened as shown in Figure 5, whereby the terminals of the arm portions act as mittens for warmth and may also act as a guard against thumb sucking. Likewise in the case of 50 the leg portions of a child's garment, the ends may be drawn over the child's foot and then tightened by means of the draw-string. A child's garment in the form of pants may also have a draw-string device used to secure the said pants 55

to the leg portions either above or below the knees as shown in Figure 2.

The draw-string construction in connection with a hem and button member is also applicable to any other circular opening of a garment.

I wish it understood that minor changes and variations in the material, position, means of affixation and integration of the parts, may all be resorted to without departing from the spirit of the invention and without departing from the scope of the appended claims.

It is furthermore understood that the application of a draw-string construction in connection with a hem and button member retains the original features of the garment and in addition, adds the above mentioned features as the tightening and enclosure elements.

I claim:

1. In a garment having openings for parts of the body, means to adjustably constrict each of said openings including a hem at the extremity of each opening, a button member secured to the outer wall of said hem and having apertures therein, a draw-string passing through the forward wall of said hem and having its ends pass-
- 20
- 25

ing through the said apertures of the button member, the ends of the draw-string being enlarged to prevent the ends of the draw-string from being drawn into the hem through the apertures, the free ends of the draw-string being detachably engageable when pulled from the hem for tightening purposes.

2. In a garment having arm and leg openings, means to adjustably constrict each of said openings either beyond or at the wrist and angle portions of the wearer, said means including a hem at the extremity of each opening having adjoining orifices on the outer wall, a draw-string passing through the said hem and having its ends terminating through the said orifices, a button member secured to the outer wall of the hem and concealing the said orifices, the said button member being provided with apertures through which the ends of the draw-string pass, the ends of the draw-string being enlarged to prevent the draw-string in thereof within the hem, the free ends of the draw string being detachably engageable when pulled from the hem for tightening purposes.
